GEARED WRENCH

William H. Johnson, Quincy, Ill.

Application April 4, 1949, Serial No. 85,425

6 Claims. (Cl. 74—789)

1

The present invention relates generally to hand tools, and more particularly to a ratchet type wrench, the rotational output of which is greater than the input.

It is an object of the present invention to provide a novel geared wrench which has a rotational output which is a multiple of the rotational input.

Another object is to provide a novel geared wrench which is selectively operative to effect a rotational output which is greater than the rotational input, or which is the same as the rotational input.

Another object is to provide a novel geared wrench which includes a ratchet construction for optionally permitting driving motion in one direction only, allowing free return of the actuating handle.

Another object is to provide a novel geared wrench of the ratchet type which is selectively operative to either tighten or loosen bolts and the like.

Another object is to provide a novel geared wrench which can be used with the regular socket attachments.

Other objects are to provide a novel geared wrench which is of rugged construction, which is relatively inexpensive to manufacture, and which can be used after a minimum amount of instruction.

Further objects and advantages of the present invention will be apparent from the following description, reference being had to the accompanying drawings wherein a preferred embodiment of the present invention is shown, in which:

Fig. 1 is a top plan view of a geared wrench embodying the teachings of the present invention;

Fig. 2 is a side elevational view of the wrench with a portion of the handle cut away and showing the slot-engaging end of the auxiliary handle in cross section;

Fig. 3 is an enlarged fragmentary plan view of the head of the wrench with the lever in the central or locked position, the planetary gearing being shown in dotted lines;

Fig. 4 is a fragmentary vertical sectional view taken on the line 4—4 in Fig. 3;

Fig. 5 is a fragmentary horizontal sectional view taken on the line 5—5 in Fig. 4, but showing the lever moved to the clockwise position;

Fig. 6 is a vertical diametrical sectional view taken on the line 6—6 in Fig. 3;

Fig. 7 is an enlarged fragmentary plan view of the neck portion of the wrench showing the lever in the counterclockwise position, the dogs and a

2

portion of the planetary gearing being shown in dotted lines;

Fig. 8 is an enlarged top plan view of a star gear;

5 Fig. 9 is an enlarged top plan view of the sun gear, showing the socket-engaging portion in dotted lines;

Fig. 10 is an enlarged side elevational view of the lever member;

10 Fig. 11 is a reduced top plan view of the auxiliary handle; and

Fig. 12 is a reduced side elevational view of the wrench assembly.

Referring to the drawings more particularly by reference numerals, 13 indicates generally a wrench assembly comprising a wrench 14 and an auxiliary handle 15, the former including a handle member 16 having a planetary gear mechanism 17 mounted in one end thereof.

20 The handle member 16 includes a rod-like end portion 18 of a size to be grasped in an operator's hand, a neck portion 20 which contains upper and lower elongated recesses 22 and 24, respectively, and a head portion 26. The head portion 25 26 has a circular opening 28 and a recessed chamber 29 adjacent thereto which extends into the neck portion 20 as shown in Fig. 5. The upper recess 22 contains three equi-spaced hemispherical cavities 30 in arcuate alignment.

The planetary gear mechanism 17 is disposed 30 in the opening 28 and includes a ring gear 31, a pair of star gears 32 each including upper and lower trunnions 33, and a sun gear 34, the last-named having an annular flange 36 and a square-shaped socket member 38 formed integral with the lower end of its shaft, and a dome-shaped boss 39 formed integral with the upper end. The inner surface of the ring gear 31 contains the usual gear teeth 40 and the outer surface contains ratchet teeth 42 (Fig. 5).

35 The diameter of each of the gears 32 and 34 is one-third of the inner diameter of the ring gear 31, so that the latter has three times as many teeth as are contained in each of the smaller gears.

40 A top cap 50 covers the upper end of the opening 28 and a bottom cap 52 covers the lower end thereof, the two caps being held together by screws 54, as shown in Fig. 6. Sleeves 56 are disposed around the screws 54 and between the two caps so as to keep them in spaced relationship, there being a slight clearance between the two caps and the head portion 26 of the handle 14 so as to permit relative rotation between the two structures.

45 55 In the lower surface of the top cap 50 (Fig.

4) there is formed a dome-like cavity 58 which receives the boss 39 of the sun gear 34, and two cylindrical-shaped recesses 60 which receive the upper trunnions 33 of the star gears 32. An undercut slot 64 is contained in the upper surface of the top cap 50 for a purpose to be described hereinafter.

A circular opening 66 is contained in the bottom cap 52 to accommodate the shaft of the sun gear 34. In the upper surface of the cap 52 there are two cylindrical-shaped recesses 68 which receive the lower trunnions 33 of the star gears 32.

A cover plate 72 is secured to the lower surface of the bottom cap 52 by means of cap screws 74. It contains a circular opening 76 which has a step-like groove 77 formed therein, as shown in Figs. 4 and 6, the horizontal surface of which supports the flange 36 so as to prevent the sun gear 34 from dropping out of the gear mechanism 16.

Bell-crank type ratchet dogs 78 and 80 (Fig. 5) are pivotally mounted in spaced opposed relationship within the chamber 29 by means of screws 82. A coil spring 84 is disposed between one pair of ends of the dogs, the other ends being free to engage the ratchet teeth 42 on the ring gear 31.

A lever 86, shown in Fig. 10, is pivotally mounted within the upper recess 24 in the handle 12 by means of a rivet 88 (Figs. 3 and 4). One end of the lever 86 is bifurcated and has downwardly extending projections 90 and 92. The other end has a small spherical-shaped detent element 94 mounted on the bottom surface for holding engagement with the cavities 30. A flat elongated projection 96 is formed integral with the upper surface of the lever 86 and extends above the sides of the recess 22, as shown in Figs. 2 and 4.

The auxiliary handle 15 includes an elongated hand portion 98 and a nose portion 100 formed to removably engage the slot 64 in the top cap 50 (Fig. 11).

Operation

The wrench assembly 13 can be used as a multiple rotational advantage ratchet type of wrench for both loosening and tightening operations, as a one-to-one ratchet type wrench for similar operations, or as a one-to-one wrench without the ratchet action.

To use the assembly as a multiple rotational advantage ratchet type wrench for a tightening operation, the lever 86 is moved in a clockwise direction until the detent element 94 engages the outermost cavity 30. This causes the dog 80 to pivot away from the ring gear 31 and the end of the dog 78 to pivot into engagement with the ratchet teeth 42 (Fig. 5). The bolt-engaging member (not shown) on the end of the socket member 38 is then positioned on the head of the bolt to be tightened, and the wrench handle 16 grasped in the operator's hand. The nose portion 100 of the auxiliary handle 15 is then inserted in the slot 64 and the handle portion 98 grasped in the operator's other hand. The auxiliary handle 15 is then reciprocated while the handle 16 is held stationary. When the auxiliary handle 15 is moved toward the handle 16, the top and bottom caps 50 and 52 rotate in a clockwise direction, thereby causing the axes of the star gears 32 to move in the same direction. Because the ring gear 31 is prevented from rotating in a clockwise direction by the dog 78, the star gears 32 will roll on the inner periphery of the ring gear 31, the teeth of the star gears engaging the gear teeth 40 of the ring gear 31. This causes the star gears 32 to rotate in a counterclockwise direction, 75

thereby rotating the sun gear and socket member 38 in a clockwise direction. Because the sun and star gears each contain only a fraction each as many gear teeth as does the ring gear 31, the former will rotate a predetermined number of times for each complete revolution of the auxiliary handle 15, thereby causing the socket member 38 to rotate a predetermined number of times as fast as the auxiliary handle 15 when it is rotated in a clockwise direction.

It will be noted that, by merely changing the relative size of the gears, one can design a wrench assembly which has a two-to-one ratio, four-to-one ratio, or any desired ratio. And, although the instant device is shown and described with two star gears, it is apparent that a satisfactory wrench can also be made using a single star gear, the extra star gear having been added primarily to increase the strength of the device and to give a balanced construction.

When the auxiliary handle 15 is moved in a counterclockwise direction, the top and bottom caps 50 and 52, and the axes of the star gears 32, rotate in a counterclockwise direction. Assuming that the frictional engagement of the bolt being tightened is great enough, the socket member 38 and the sun gear 34 will not rotate when the axes of the star gears are rotated in a counterclockwise direction. Therefore, the star gears 32 will roll on the sun gear 34 and rotate in a counterclockwise direction. This causes the ring gear 31 to be rotated in a counterclockwise direction, the end of the dog 78 riding over the ratchet teeth 42. The end of the dog 78 is held in engagement with the ratchet teeth 42 by the action of the spring 84, so that, when the auxiliary handle 15 is again moved in a clockwise direction, the ring gear 31 will be prevented from rotating thereby causing the cycle to be repeated.

It is apparent that, if the operator's arm becomes tired, he can hold the auxiliary handle 15 stationary and reciprocate the wrench handle 16 with his other hand, and thereby achieve the same results.

To use the wrench assembly 13 as a ratchet type multiple rotational advantage wrench for loosening bolts and the like, the lever 86 is moved in the counterclockwise direction into the position shown in Fig. 7. This causes the dog 78 to be pivoted away from the ring gear 31 and the end of the dog 80 to be pivoted into engagement with the ratchet teeth 42. Thereafter, a counterclockwise movement of the auxiliary handle 15 will cause the socket member 38 to rotate in a counterclockwise direction at a predetermined number of times the speed of the auxiliary handle in a manner similar to that described above. Also, clockwise rotation of the auxiliary handle 15 will cause the ring gear 31 to rotate in the clockwise direction with the dog 80 riding over the ratchet teeth 42.

To use the assembly 13 as a one-to-one wrench with a ratchet action, the end of the lever 86 is moved to either side as described supra, and the wrench handle 16 and the auxiliary handle 15 rotated together in the same direction. Assuming that the lever 86 is in the position shown in Fig. 5, and that the wrench handle 16 and the auxiliary handle 15 are brought together and grasped by the operator in one hand, a clockwise rotation of the handles will cause the star gears 32 to attempt to roll around the sun gear 34 and to rotate in a clockwise direction. This would also tend to cause the ring gear 31 to rotate in a clockwise direction, but, because it is prevented,

from doing so by the end of the dog 78 being in engagement with the ratchet teeth 42, the ring gear 31 and the star gears 32 will rotate together. Because there is no relative rotation between the sun gear 34, star gears 32, and the ring gear 31, the sun gear 34 and the socket member 38 on its shaft will rotate in the same direction and at the same speed as the handles. Assuming, as above, that the frictional engagement of the bolt is great enough, counterclockwise rotation of the handles will cause the star gears 32 to roll around the stationary sun gear 34 in a counterclockwise direction. This causes the star gears 32 to rotate in a counterclockwise direction and to rotate the ring gear 31 in the same direction with the end of the dog 78 riding over the ratchet teeth 42. The spring 84 holds the end of the dog 78 against the ratchet teeth 42, however, so that, when the handles are again moved in the clockwise direction, the gears will rotate together and the cycle will be repeated.

To use the assembly in the same manner for loosening a bolt or the like, the lever 86 is moved into the position shown in Fig. 7 and the rotation of the gears are exactly opposite to that described above.

If it is desirable to use the assembly as a one-to-one wrench without the ratchet action, the lever 86 is placed in the central position, as shown in Fig. 3, and the wrench handle 16 and the auxiliary handle 15 rotated together. Because both of the dogs 78 and 80 engage the ratchet teeth 42, the ring gear 31 cannot rotate within the head portion 26 of the handle member 16, thereby preventing a ratchet action in either direction.

Thus, it is apparent that there has been provided a construction which fulfills all of the objects and advantages sought therefor.

It is to be understood that the foregoing description and the accompanying drawing have been given only by way of illustration and example, and that changes and alterations of the present disclosure, which will be readily apparent to one skilled in the art, are contemplated as within the scope of the present invention, which is limited only by the claims which follow.

What is claimed is:

1. In a device of the class described, the combination of an elongated handle member containing an opening adjacent one end thereof, a ring gear with gear teeth on the inner periphery and ratchet teeth on the outer periphery rotatably mounted within said opening, a sun gear and a star gear rotatably mounted within the ring gear, the star gear being in engagement with both the sun gear and the ring gear, a pair of ratchet dogs having ratchet teeth engaging ends and operating ends pivotally mounted intermediate said ends on the handle member adjacent the ring gear for engagement therewith, and operating means for selectively engaging both or either of the dogs with the ratchet teeth on the ring gear whereby the latter is prevented from rotating or from rotating in one direction.

2. In a device of the class described, the combination of an elongated handle member containing an opening adjacent one end thereof, a ring gear with gear teeth on the inner periphery and ratchet teeth on the outer periphery rotatably mounted within said opening, a sun gear and a star gear rotatably mounted within the ring gear, the star gear being in engagement with both the sun gear and the ring gear, a pair of ratchet dogs pivotally mounted on the handle member adjacent the ring gear, and a bifurcated lever-like

member for selectively engaging both or either of the dogs with the ratchet teeth on the ring gear whereby the latter is prevented from rotating or from rotating in one direction.

3. In a device of the class described, the combination of a handle member having an opening formed therein, a ring gear with gear teeth on the inner periphery thereof rotatably mounted within said opening, a sun gear and a star gear rotatably mounted within the ring gear, the star gear being in engagement with both the sun gear and the ring gear and rotatable completely about the sun gear, a connecting member containing openings rotatably receiving the ends of the sun and star gears and rotatable 360 degrees relative to the handle member, an auxiliary handle removably attached to the connecting member, and means for selectively preventing rotation of the ring gear in one direction relative to the handle member.

4. In a device of the class described, the combination of a handle member having an opening formed therein, a ring gear with gear teeth on the inner periphery thereof rotatably mounted within said opening, a sun gear and a star gear rotatably mounted within the ring gear, the star gear being in engagement with both the sun gear and the ring gear and rotatable about the sun gear, a pair of cap-like members rotatably mounted on each side of the ring gear, means fastening the cap-like members together, said cap-like members containing openings rotatably receiving the ends of the sun and star gears, means on one cap-like member for removably fastening an auxiliary handle thereto, said cap-like member being spaced from the handle member and the fastening means being adjacent the outer surface thereof so that the auxiliary handle passes over the handle member for 360 degrees rotation relative thereto, and means for selectively preventing rotation of the ring gear in one direction relative to the handle member.

5. A geared wrench, comprising a handle member having an opening formed therein adjacent one end; a ring gear with gear teeth on the inner periphery thereof rotatably mounted within the opening; a sun gear and at least one star gear rotatably mounted within the ring gear, the star gear being in engagement with both the sun gear and the ring gear and rotatable about the sun gear; means for rotating the star gear in either direction about the sun gear; and manually engageable means including ratchet dogs pivoted intermediate their ends for engaging said ring gear and mounted on the handle member for selectively preventing the ring gear from rotating relative to the handle member or from rotating in either one direction or the other relative thereto.

6. In a device of the type described, an elongated handle member having an enlarged portion adjacent one end which contains a circular opening; a ring gear with gear teeth on the inner periphery and ratchet teeth on the outer periphery thereof rotatably mounted within the opening; a sun gear and at least one star gear rotatably mounted within the ring gear in operative engagement therewith, the lower end of the shaft of the sun gear extending beyond the confines of the handle member; upper and lower cap members closing each side of the opening, said cap members being rotatably mounted relative to the handle member and the ring gear, said cap members containing recesses rotatably receiving the ends of the sun and star

gears and an opening through which the lower end of the shaft of the sun gear extends; means fastening the cap members together; a pair of ratchet dogs pivotally mounted on the handle member adjacent the ring gear; a lever member for selectively engaging both or either of the dogs with the ratchet teeth on the ring gear for preventing the latter from rotating relative to the handle member or from rotating in one direction relative thereto; and an auxiliary handle for rotating the cap members and the star gear relative to the handle member.
